(57) **CLAIM**

The ornamental design for a satellite terminal (receiver) with parabolic antenna, as shown and described.

DESCRIPTION

FIG. 1 is a front perspective view of the satellite terminal (receiver) with parabolic antenna of the present invention;

FIG. 2 is a front elevation view of the satellite terminal (receiver) with parabolic antenna of the present invention;

FIG. 3 is a rear elevation view of the satellite terminal (receiver) with parabolic antenna of the present invention;

FIG. 4 is a left side elevation view of the satellite terminal (receiver) with parabolic antenna of the present invention;

FIG. 5 is a right side elevation view of the satellite terminal (receiver) with parabolic antenna of the present invention;

FIG. 6 is a top plan view of the satellite terminal (receiver) with parabolic antenna of the present invention; and,

FIG. 7 is a bottom plan view of the satellite terminal (receiver) with parabolic antenna of the present invention.

In the drawings, the broken lines depict environmental subject matter only and form no part of the claimed design.

UNITED STATES PATENT AND TRADEMARK OFFICE
CERTIFICATE OF CORRECTION

PATENT NO. : Des. 597,085 S
APPLICATION NO. : 29/300149
DATED : July 28, 2009
INVENTOR(S) : Jens Andersson

Page 1 of 1

It is certified that error appears in the above-identified patent and that said Letters Patent is hereby corrected as shown below:

On the Cover Page of the patent

Line (73), please correct the Assignee as follows:

Change "Propeller Design AB, Stockholm (SE)" to
--Swe-Dish Satellite Systems AB, Solna (SE)--.

Signed and Sealed this

Seventeenth Day of November, 2009

David J. Kappos
Director of the United States Patent and Trademark Office
